ARTHUR A. BACKHAUS, OF BALTIMORE, MARYLAND, ASSIGNEE TO U. S. INDUSTRIAL
ALCOHOL CO., A CORPORATION OF WEST VIRGINIA.

PRODUCTION OF HALOGENATED HYDROCARBONS.

1,402,337.

Specification of Letters Patent. Patented Jan. 3, 1922.

Application filed May 7, 1919. Serial No. 295,473.

To all whom it may concern:

Be it known that I, ARTHUR A. BACKHAUS, a citizen of the United States, residing at Baltimore, in the State of Maryland, have 5 invented a certain new and useful Improvement in the Production of Halogenated Hydrocarbons, of which the following is a specification.

My invention relates particularly to a 10 process of producing halogenated hydrocarbons, but has reference especially to the production of ethylene dichloride.

The object of my invention is to provide a process by means of which unsaturated hydrocarbons may be halogenated by 15 addition rather than substitution, and especially by means of which process ethylene dichloride may be made from ethylene in an advantageous manner and with a high yield. 20 Further objects of my invention are to provide a process of the above character which is operated with the exclusion of light, the maintenance of an excess of the unsaturated hydrocarbon, such for example as ethylene, 25 throughout the treatment, and the maintenance of a comparatively low temperature during the treatment.

Further objects of my invention will appear from the detailed description thereof 30 set forth hereinafter.

While my invention is capable of being carried out in many different ways, for the purpose of illustration I shall describe only certain ways of carrying out the same hereinafter, and while it is capable of being carried out in connection with many different types of apparatus, I have shown only one type of apparatus for use in connection therewith in the accompanying drawings, in 40 which;

The figure is a diagrammatic representation partly in section of an apparatus which may be used in accordance with my invention.

45 Assuming that the process is to be carried out by the treatment of ethylene with chlorine to produce ethylene dichloride, ethylene gas may be conveyed by means such as pipe 1 into a chamber such as is shown at 2.

This is preferably formed by a cover plate 3, which is shown as secured to a cylindrical casing 4, in such a manner as to hold between the cover plate 3 and the cylinder 4 a perforated plate 5, carrying in the same 55 the ends of a series of tubes 6. These are

shown as held in place in a similar manner at their lower ends by means of a perforated plate 7, located between the cylinder 4 and a bottom plate 8, which form a chamber 9 at the lower end of the apparatus. The cylinder 4 is kept cool by means such as a counter-current of water which is admitted by a pipe 10, and which flows out of the cylinder 4 by means of a pipe 11. Chlorine gas is preferably admitted to the chamber 2 by means such as a pipe 12 in the proportion of ten volumes of chlorine to eleven volumes of ethylene, these proportions being chosen so as to maintain at all times throughout the treatment an excess of ethylene present. In 70 this embodiment the chlorine and ethylene after entering the chamber 2 pass downwardly through the tubes 6, where they become united to form ethylene dichloride, the temperature being kept low at all times by means of e. g., the current of water in the cylinder 4. The ethylene dichloride together with some chlorine dissolved therein, and some gaseous ethylene, pass out of the chamber 9 by means such as a pipe 13 and into 80 a receiver 14, where the pipe 13 preferably terminates as near the bottom of the receiver as possible, so as to form a liquid seal within the receiver. The liquid within the receiver 14 will at first be comprised of 85 ethylene dichloride having chlorine dissolved therein. As the process continues to be carried out, the gaseous ethylene which descends in the pipe 13 will be bubbled through the liquid in the receiver 14, so as to 90 combine with all the chlorine which is dissolved in the liquid, so that in this manner ethylene dichloride entirely free from any uncombined chlorine is obtained, and may be drawn off from time to time through a 95 valved pipe 15 in the bottom of the receiver. In this embodiment the excess of the ethylene passes out of the receiver 14 by means such as a pipe 16, preferably which conducts the ethylene back to the chamber 2, where the 100 ethylene is thus again brought into contact with chlorine, so as to form ethylene dichloride in the same manner as previously described.

It will be understood that all of the apparatus above described is ordinarily made of an opaque material of such a character as not to be acted upon by the substances present, and may for example be made throughout of iron. The temperature is kept as low 110

as possible, and in any event as low as 50° C., as indicated by the temperature in the materials flowing out of the chamber 9. By excluding the light and keeping the temperature as low as possible, very high yields are obtained, that is to say 96 and 97% of the ethylene treated is changed to ethylene dichloride, inasmuch as in this manner substitution of hydrogen atoms by the halogen used is obviated. Furthermore, it will be understood that instead of ethylene other unsaturated hydrocarbons may be used, as for example butylene or amylene, and that instead of the chlorine the other halogens may be used.

While I have described my invention above in detail, I wish it to be understood that many changes may be made therein without departing from the spirit thereof.

I claim:

1. The process of forming pure olefine dihalide comprising passing a halogen and olefine through cooled tubes in a continuous

stream, collecting the dihalide, bubbling said stream therethrough, and continually re- 25 turning the uncombined gas to the stream entering the tubes.

2. The process of forming pure olefine dihalide comprising passing the halogen and olefine through cooled tubes and collecting 30 the dihalide formed, bubbling the halogen and olefine through the dihalide formed, and returning the uncombined halogen and olefine to the entrance of the tubes.

3. The process of forming pure ethylene 35 dichloride comprising passing chlorine and ethylene through cooled tubes and collecting the ethylene dichloride formed, bubbling the chlorine and ethylene through said ethylene dichloride, and returning the uncombined 40 ethylene and chlorine to the entrance of the tubes.

In testimony that I claim the foregoing, I have hereunto set my hand this 22nd day of April, 1919.

ARTHUR A. BACKHAUS.
